UNITED STATES PATENT OFFICE.

SAMUEL T. PERKEY, OF GRAHAM, VIRGINIA, ASSIGNOR OF TWO-THIRDS TO CHARLIE W. WADE AND THOMAS L. FELTS, AS JOINT TENANTS, BOTH OF BLUEFIELD, WEST VIRGINIA.

RAILWAY-MAIL-BAG CATCHER AND DELIVERER.

Application filed April 10, 1922. Serial No. 551,186.

To all whom it may concern:

Be it known that I, SAMUEL T. PERKEY, a citizen of the United States, residing at Graham, in the county of Tazewell and State of Virginia, have invented certain new and useful Improvements in Railway-Mail-Bag Catchers and Deliverers; and I do hereby declare the following to be a full, clear, and exact description of the invention, such as 10 will enable others skilled in the art to which it appertains to make and use the same.

This invention relates to new and useful improvements in railway mail bag catchers and deliverers and has for its primary object the provision of a car device adapted to deliver to and receive from a specially constructed crane, a mail bag to obviate any possible chance of the delivered bag being lost or destroyed and which device is so, 20 mounted that it may be easily and quickly positioned out of the way of the mail clerk and to one side of the doorway of the car when not in use.

Another object of this invention is the provision of means that permits of the bag delivering and catching device to be adjusted into its different positions and also permits of the device to be changed from one side of the car to the other when desired.

30 A further object of this invention is the provision of a mail bag catcher and deliverer of the above stated character which will be simple, durable and efficient, and which may be manufactured and sold at a comparatively low cost.

With these and other objects in view as will become more apparent as the description proceeds, the invention consists of certain novel features of construction, combination and arrangement of parts as will be hereinafter more fully described and claimed.

40 For a complete understanding of my invention, reference is to be had to the following description and accompanying drawings, in which:—

Figure 1 is a perspective view illustrating a mail bag catcher and deliverer applied to a fragmentary portion of a railway mail car, 50 and operating in conjunction with a crane.

Figure 2 is a detail view of the deliverer and catcher.

Referring in detail to the drawings, the numeral 1 indicates as an entirety a crane

for the purpose of receiving from and delivering to a passing train or mail car a mail bag, and is mounted upon a platform 2 arranged next to the track, or, if used in conjunction with a double track system, is positioned between the tracks. A pedestal 3 is 55 carried by the platform 2 and has rotatably mounted thereon a vertical standard 4 held against accidental rotation with respect to the pedestal by means of a locking lever 5 adapted to engage any one of a series of 60 teeth 6 on the lower end of the standard. Upper and lower mail bag supporting arms 7 and 8 are secured to the vertical standard 4 and extend horizontally therefrom and are equipped at their ends with mail bag engaging rods 9 that extend at right angles to the arms 7 and 8 and also extend on opposite sides of said arms for the purpose of supporting a mail bag at either side of the arms, thereby permitting the device to be 70 used on a single track system where the mail cars or trains travel in opposite directions on the same track. The arms 7 and 8 are positioned in vertical alinement, while the rods 9 thereof are adapted to extend through the usual rings 10 at the ends of the mail bag 11. If the crane is to be used in conjunction with a double track system, the standard 4 may be rotated by releasing the lever 5 from the teeth to position the bag 75 supporting arms adjacent either of the tracks. An intermediate arm 12 carried by the standard 4 is arranged in vertical alinement with the arms 7 and 8 and carries at its ends a receiving element 13 in the form of 80 an elongated plate having inwardly extending notches 14 in its ends adapted to receive and catch a mail bag delivered from a passing car or train.

85 A vertical standard 15 is located adjacent the doorway of the car, and has formed thereon a bearing portion 17 to be engaged by a supporting bar or element 18. The bar or element 18 has attached thereto a mail bag deliverer and catcher constructed in accordance with my invention and one end of the bar is reduced and bifurcated so that it may be applied to the standard 15 and rest upon the bearing portion 17. The reduced bifurcated end of the bar or 100 element 18 is provided with a removable clip 19 which will permit the bar or element to swing about the vertical standard 105

and to permit the removal of the bar from the standard when desired. The other end of the bar or element is reduced to form an extension 20 adapted to engage a clip 21. 5 The clip 21 is located at the doorway for the purpose of cooperating with the standard 15 in supporting the element or rod 18 across the doorway while a clip 22 is secured to the side of the car to receive the extension 10 20 when the deliverer and catcher is positioned in an inoperative position.

The extension 20, when in engagement with the clip 22, causes a positioning of the catcher and deliverer in close proximity to 15 one of the side walls of the car and away from the doorway so that the device will not interfere with the movements of the mail clerks. It is to be understood that a standard 15 and the clips 21 and 22 are applied to each side of the car so that the element 18 may be transferred from one side of the car to the other according to the direction of travel.

A mail bag supporting arm 23 includes a 25 vertical portion 24 which is secured to the bar or element 18 and projects above and below the latter and has its upper and lower portions bent to form horizontal arms 25 that carry at their outer ends mail bag 30 attaching rods 26 that are disposed horizontally and project beyond opposite sides of the arm portions 25 and are adapted to pass through the rings at the ends of a mail bag and to permit the supporting 35 of a mail bag at either side of the horizontal arm portions 25 so that the device may be used regardless of which direction the car 16 is traveling. A mail bag when applied to the rods 26 is supported by 40 the arm 23 outside of the car so that it may be caught by the catcher 13 on the crane 1, when the car passes the crane.

A catcher 27 is carried by the bar or element 18 and comprises an elongated plate 45 29 having inwardly extending slots or notches 30 in its ends to form forked end portions to the catcher adapted to receive or catch a mail bag supported by the crane and permit the device to be used regardless 50 of which direction the car 16 is traveling.

The plate 29 is secured to the outer end of a horizontal arm 31 carried by the bar or element 18 and is arranged in vertical aline-

ment with the horizontal arm portion 25 of the mail bag supporting arm 23. The catcher 27 is located in a plane slightly below the plane of the catcher on the crane so that during the passing of the car the catchers will not come in contact with each other and also the mail bag attaching rods of the car device and of the crane are arranged in planes so that they will not come in contact with each other.

While I have shown and described the preferred embodiment of my invention, it will be understood that minor changes in construction, combination and arrangement of parts may be made without departing from the spirit and scope of the invention as claimed.

Having thus described my invention, what I claim is:

1. A mail catcher mechanism including a bar, means to secure said bar horizontally and at a car doorway, a vertical support 75 carried by and extending above and below the bar, arms extending forwardly from the upper and lower end portions of the support, catcher rods carried by the arms and disposed substantially parallel to the bar, a receiving element extending forwardly from the bar intermediate said arms, said arms having a reduced end, a clip detachably engageable by said end through sliding movement, a standard, and the other end of the bar having a clip removably engageable with the standard.

2. A mail catcher mechanism including a bar, means to secure said bar horizontally and at a car doorway, a vertical support 90 carried by and extending above and below the bar, arms extending forwardly from the upper and lower end portions of the support, catcher rods carried by the arms and disposed substantially parallel to the bar, a receiving element extending forwardly from the bar intermediate said arms, said arms being integral with the support, and said receiving element having notches in its opposite ends for the purpose specified.

In testimony whereof I affix my signature in presence of two witnesses.

SAMUEL T. PERKEY.
